UNITED STATES PATENT OFFICE.

FREDERICK C. MEACHAM, OF GARDEN CITY, NEW YORK.

DEVICE FOR INDICATING TIME.

Application filed April 27, 1926. Serial No. 104,937.

My invention relates to a device for use in the determining of time by observing the position of certain stars; this is accomplished by setting my device, so that the 5 relative position of the stars, followed by certain calculations, or by direct readings indicate the time when the observations are made, as will be hereinafter fully set forth. The object of my invention is to produce a 10 simple and inexpensive device which will permit the quick and easy determination of the relative positions of the "North Star" and the "Pointers" in "Ursa Major" with a remarkable degree of accuracy under the 15 conditions in which the device is ordinarily used; another object of my invention is to provide a device for such purpose and other purposes, such as those relating to navigation, which shall be compact and easily portable and which at the same time may be 20 capable of refinement in accuracy of manufacture for various uses.

Fig. 1 of the accompanying drawing is a plan view of one form of my device and 25 indicates a method of using the device. Fig. 2 is a plan view of an improved modification thereof.

This application is a continuation in part 30 of my prior application filed November 13, 1925, Serial No. 68,815, in which the device of Fig. 1 is fully illustrated and described.

In Fig. 1 of the drawing, 21 represents a disk which may be of transparent material, such as celluloid. The disk is preferably divided into four equal sectors by the 35 perpendicular diameters 25, 26. The periphery of the disk is also divided into twelve equal spaces by the diameters and the lines indicated at 22 or by other suitable means 40 for indicating the divisions of the disk; these spaces are again preferably divided, as by the lines 23, 24, into four equal parts. The lines 22, as well as the outer extremities 45 of the two diameters, may be numbered, as indicated at 27, in the same manner as the dial of a clock, from "1" to "12" inclusive. At the outer end of one diameter, adjacent the numeral "12", I prefer to place an outwardly pointing arrow-head, or other easily 50 noticeable mark 28, to indicate clearly the uppermost point of the disk which corresponds to the zenith.

In this form of the device, a central aperture is stamped out of the material of the 55 disk and a small metallic eyelet 29 inserted therein. Carried by the eyelet 29 is an arm

30 which may be transparent. The arm, when extended, projects beyond the outer edge of the disk. The eyelet is riveted over a portion of the arm to hold it in rotatable 60 relation to the disk. The eyelet 29 is preferably a true eyelet—i. e., of such character that it will not obstruct clear vision through the aperture at the center of the disk. The arm 30 has preferably a length about equal 65 to the diameter of the disk and it may be slotted throughout approximately half of its length, as indicated at 31, so that, when the device is not in use, the arm may slide along the eyelet over the face of the disk 70 so that its end will extend but slightly beyond the edge of the disk. It will be understood that this is merely for compactness and convenience in carrying. The longitudinal center of the arm is defined, as by the 75 line 32, which preferably extends from the outer end of the arm to a point which (when the arm is fully extended) meets or crosses the edge of the disk. It will of course be understood that any other suitable means 80 may be used to define, by means of the arm, a radial line; for example, the outer end of the arm may be offset so that one edge thereof lies along a radius (extended) of 85 the disk.

I will now describe one method of using my device; this method enables a surprisingly accurate calculation of time, at least when used at or near a line of longitude which determines the standard time for that 90 locality. Of course, when my device is used at some distance east or west of such line of longitude, the calculated time will not agree so well with the standard time, but it will everywhere agree very closely with 95 the true time or sun-time.

In the method here described, my device is used to determine the relative position of the North Star or Polaris and the two stars in the constellation Ursa Major known as 100 "Alpha" and "Beta" or the "Pointers". My device is held before the eyes of the observer—say eight inches from the eyes, with the arrow-head 28 pointing toward the zenith and the diameter 25 in vertical position. The presence of the two diameters on the face of the disk assists the observer in properly positioning it. The disk should be held so as to lie in a plane perpendicular 105 to the line of vision between the observer and Polaris. The arm 30 having been fully extended, the device is then so positioned 110

that Polaris is visible through the hole at the center of the disk—as indicated at 33 in the drawing. The arm 30 is then rotated, without disturbing the position of the disk, 5 until the "Pointers" of the constellation Ursa Major, indicated at 34, 35, lie along the line 32 or the line 32 if continued. This adjustment having been made, the relative position of the stars is read by taking the 10 reading on the disk as determined by the position of the line 32.

Suppose, for example, the reading is, as indicated in the drawing, approximately 1½; suppose also that the reading is taken 15 on August 8 in any year. Then to determine the time the following calculations are made: Start with the reading—in this case, 1½; add to that the number of months and the fraction that have elapsed during the 20 calendar year—in this case 7½ (January to July, inclusive, being 7 and the eight days of August being approximately one quarter); the sum then equals 8¾; next, double this sum—giving, in this case, 17½; subtract this final amount from 40½—giving 22¾. This last figure gives the time. Where, as here, the time given is greater than 12, then 12 or 24 or 36, may be deducted 25 so that the net result will be less than 12. 30 Proceeding thus in the example given, 12 is deducted from 22¾, leaving 10¾—which means that the time is 10.45.

The modified form illustrated in Fig. 2 of the drawings is based upon the same principles above described in connection with Fig. 1 of the drawings. In this device, however, it is unnecessary to calculate time in hours after the readings of the disk have 35 been made.

40 Referring to Fig. 2, the numeral 41 indicates a disk similar to that of 21 in Fig. 1, and may be made of any suitable sheet material having the necessary degree of stiffness. The margin of this disk however, 45 is divided into twenty four equal parts numbered as two series of 12 each, representing the two sets of 12 hours of any one day, as indicated at 42—43. The spaces between the longer hour marks may be divided into four parts, indicating quarter hours or any number of corresponding parts indicating other fractions of an hour. Within the outer 50 margin of the disk 41 is a second series of divisions, the main portions of which constitute 12 spaces representing the twelve months of the year from January to December, as indicated by the numerals 44. The spaces between the longer lines forming 55 these divisions are preferably divided into six equal parts, which correspond respectively to the 5th, 10th, 15th, 20th and 25th days of the respective months. Obviously, 60 these divisions may be arranged to cover shorter periods, depending upon the size of 65 the apparatus in which they are embodied.

The disk 21 is provided with a central aperture, through which passes a small metallic tubular member or eyelet, providing a small hole through which a sight may be taken, as indicated at 45. The eyelet 45 70 retains in position an arm 46 which is provided with a central longitudinal slot 47 whose length is practically the same as the radius of the disk 41. The outer end 48 of the arm 46, if not made of transparent 75 material as above described, is preferably cut away along a central longitudinal line, as indicated at 49, so that the edge formed by said cutaway portion may be used as a sight to enable the arm to be positioned on 80 the "Pointer" stars, as above described. A short line or marker 50 is provided on the arm 46 and is so located when the arm is extended to come opposite to the divisions on the hour scales 42 and 43. These parts 85 are arranged to be movable in relation to the disk, substantially as described in connection with Fig. 1. The eyelet 45 also retains in position a second slotted arm 51, similar to the arm 46, but having a somewhat shorter slot 52, the end of which when the arm is extended is so positioned as to allow the divisions in the circular scale 44 90 to be observed therethrough. This arm is also provided with a central marking line 53, which will indicate the exact position of the arm 51 on the disk, so that it may be placed opposite the nearest date on the circular scale 44. The manner of using this 95 form of my device may be described as follows: The arm 51 is pulled outward as far as possible and then is rotated until the line 53 comes opposite the date on which the observation is being made. The disk is then placed before the eyes in the same manner as described in connection with the 100 device of Fig. 1, so that the North Star will be seen through the eyelet 45, and as near as possible to the center of the eyelet. The disk and the arm 51 are then rotated in 105 unison so that the center line of the arm 51 lies as near as possible in a vertical plane, passing through the North Star and the body of the observer, the disk itself being held so as to lie in a plane perpendicular to 110 the line of vision between the observer and the North Star.

The arm 46 is then rotated about the eyelet 45 until one or both of the two "Pointer" stars of Ursa Major lie on the line 49. The 115 parts are then in position for a direct reading of the hour at which the observation is taken. In the drawing, as shown in Fig. 2, the line 53 is set at a division corresponding to April 15th. With the two "Pointer" 120 stars in the position shown in Fig. 2, the line 50 comes between the division indicating 4.00 o'clock and the next division indicating 4.15, and is practically one-third 125 of the distance between said divisions, thus 130

indicating that the time of the observation was approximately five minutes past 4.00 o'clock in the morning. It will thus be seen that this form of the device does away with any intermediate calculations and the time may be read directly from the margin of the disk, obviously simplifying the use of the device as described in Fig. 1, although the principles involved in such use are the same as previously indicated.

From the above description, it will be apparent that these devices may be used for other purposes than solely for indicating time, that is, they may be adapted for use as instruments to determine longitude, and when used in connection with the usual navigational tables may also be employed to determine latitude. In determining longitude, it will be apparent that when the hour 20 of the day corresponding to the reference meridian is known by means of a chronometer and the time of the observation determined as above described, the difference between these respective times will indicate the time consumed in the angular rotation 25 of the earth beyond said reference meridian adjacent to which the device is designed to be used, it being understood, of course, that either one or both of the "Pointer" stars are 30 on the reference line of the arms 30 or 46 and the Polar star is observed through the central eyelet 33 or 45. The angular rotation thus found will give the difference in 35 longitude between the reference meridian and the point of observation.

As above stated, I am aware that modifications may be made by those skilled in the art in my device for indicating time. I therefore do not wish to be understood as 40 being limited to the details of form and arrangement of parts herein described, but desire protection for all forms of my device as may come within the spirit and scope of the appended claims.

It will also be apparent that the device is 45 capable of much refinement in design and manufacture, and may be constructed as a precision instrument by the use of usual telescopic sights, vernier scales and other devices used in connection with accurate astronomical instruments.

What I claim and desire to protect by Letters Patent is:

1. A stellar time indicator comprising a 50 body provided with a plane surface having a scale thereon whose divisions represent fractions of a day and provided with means for sighting and coordinating with said scale, one of the stars being observed, means 55 carried on said body for sighting and determining the radial direction of another of said stars with reference to the divisions of said scale, and means for indicating the re-

quired fixed position on which said scale is to be placed with reference to said stars. 65

2. A stellar time indicator comprising a plate having a central opening and a plurality of divisions at its margin representing the fractions of a day and arranged in circular series and having indicating means for determining the required fixed position on which said scale is to be placed with reference to the zenith, and a member rotatable about said central opening and provided with a reference line adapted to be placed 70 to intersect one of said stars. 75

3. A stellar time indicator comprising a disk having a central opening and a marginal scale, means for indicating the position on which a diametral line of the disk is to 80 be placed with reference to the zenith when an observation is being made, and a movable member adapted to rotate about said opening and having a reference line adapted to be placed so as to intersect one of the stars 85 being observed and to indicate certain divisions on said scale.

4. A stellar time indicator comprising a disk having a central opening and its margin having a scale divided into equal main divisions representing hours of the day, the marks forming such divisions being numbered consecutively from 1 to 12, there also being means for indicating the position on which a diametral line of the disk is to be 90 placed with reference to the zenith when an observation is being made, an arm pivoted to rotate about said central opening in the disk and provided with a reference line adapted to be placed to intersect one of a 100 plurality of stars being observed and to indicate certain divisions on said scale. 95

5. A stellar time indicator comprising a disk having twenty four main divisions thereon, representing two sets of twelve 105 hours of a day each, and also having a second scale whose main divisions represent the twelve months of a year and whose minor divisions represent equal numbers of days 110 in each month, said disk having a central opening, through which the North Star may be observed, a pivoted member adapted to rotate about said opening in the plane of said disk, and having a reference line adapted to be placed to intersect another 115 of the stars being observed and to indicate the hour of observation on said disk, and a second member rotatable about said central opening having a reference line adapted to be set on the date of observation as provided 120 on said disk, said line also being adapted to be directed toward the zenith in a plane substantially at right angles to a line connecting the observer with the North Star.

FREDERICK C. MEACHAM.
